The ornamental design for a packet with integral connector tab, as shown and described.

DESCRIPTION

FIG. 1 is a perspective view of a packet with integral connector tab in accordance with the present invention;

FIG. 2 is a front elevation thereof;

FIG. 3 is a rear elevation thereof;

FIG. 4 is a side elevation thereof;

FIG. 5 is an opposite side elevation thereof;

FIG. 6 is a top plan view thereof;

FIG. 7 is a bottom plan view thereof; and,

FIG. 8 is a front elevation of the packet with integral connector tab of FIG. 1, with a circular aperture.

In the drawings, the dashed lines in FIGS. 1-8 are included to show environmental features and portions of the packet with integral connector tab that form no part of the claimed design.
